REPLACEABLE MULTIPLE UNIT FUSE PLUG

William T. Stanley, Indianapolis, Ind.

Application January 5, 1951, Serial No. 204,509

5 Claims. (Cl. 200—125)

1

This invention relates to a screw type fuse plug wherein a replaceable fuse element in multiple form may be replaced. A primary object of the invention resides in the fact that the structure may be constructed to occupy substantially the same space as that of the present, single fuse unit type. A further primary object of the invention is to provide a fuse device of the nature indicated wherein there will be a high safety factor in that the parts will be so spaced as to avoid any normal shorting across from conductor to conductor.

A still further primary object of the invention is to provide a fuse structure which may be loaded and unloaded for replacing purposes by any ordinary householder without the use of tools of any sort. A still further important object of the invention is to provide a replaceable unit which may be relatively low in cost so that in the long run, over a period of time, there will be affected a considerable saving in cost over and above the heretofore practice of having to buy separate single fuse units.

These and many other objects and advantages of the invention will become apparent to those versed in the art in the following description of one embodiment as illustrated in the accompanying drawing, in which

Fig. 1 is a view in side elevation in partial section of a structure embodying the invention;

Fig. 2 is a top plan view of the structure;

Fig. 3 is a view in section on the line 3—3 in Fig. 2;

Fig. 4 is a view in bottom plan of the fuse unit;

Fig. 5 is a view in side elevation of the fuse unit;

Fig. 6 is a view in top plan of the fuse unit; and

Fig. 7 is a view in transverse section on the line 7—7 in Fig. 6, with the fuse material removed.

The views in the drawing are on a scale of approximately twice actual size of the device embodying the invention.

A base 10 is formed to have the lower portion shaped in the usual manner to receive therearound a conducting ferrule 11 having screw-threads 12 which will engage in the usual fuse receptacle (not shown). The body 10 is made out of any suitable insulating material such as porcelain, the material being not of the essence of the invention, but being necessarily a good dielectric.

The upper portion of the body 10 flares outwardly into a head portion 13 which is essentially a cup having a lower floor therein designated by the numeral 14.

Along the side of the body 10 extending up inside of the ferrule 11, is a conductor 15 which has its upper end 16 passed through the floor 14 and turned inwardly thereover a distance to-

2

wards the axis of the body 10. The conductor 15 is maintained in an electrical contact with the ferrule 11.

Axially extending through the body 10 in more or less fixed position therein, is a post 17 having an external contact head 18 across the lower end of the body 10 spaced in an insulating manner from the lower end of the ferrule 11. This post 17 extends up through the body 10 to receive screwthreadedly on a portion thereof a nut 19 which bears compressibly against the floor 20 formed in a counterbore 21 in the floor 14. From the nut 19, the post 17 extends in a continuing and axial manner upwardly therefrom by a reduced diameter end 22.

A fuse carrier 23 is formed in a circular manner to be essentially a disk, and has an external diameter less than the internal diameter of the cup 13. This carrier 23 is made out of any suitable dielectric material, a ceramic material being suitable, although any of the electrically insulating plastics may be employed.

In the present showing, there is provision made for six fuse operative elements which will hereinafter be described. To accommodate these individual elements, the carrier 23 is formed into six general compartments on the top side designated by the numerals 24—29 inclusive. These compartments each are open from the top side, and are defined by intervening vertically disposed partitions 69 which extend radially inwardly toward the axis to open into a central passageway 30 extending entirely through the carrier 23. In other words these various walls 69 extend vertically downwardly from their individual compartments to form vertically disposed ribs 31 within the passageway 30. The underside of the carrier 23, Fig. 7, is provided with an upwardly extending counterbore 32 so as to leave an annular flange 33 around the marginal portion of the carrier 23 to extend downwardly.

The top side of the carrier 23 is bounded by an upturned flange 34 which forms the outer wall of each of the various compartments 24—29. The top edge of this flange 34 is in the same plane as the top edges of the various walls 69. Between each adjacent pair of walls 69, the flange 34 is notched as at 35, centrally between the outer ends of the walls 69.

A fuse spider generally designated by the numeral 36 is formed to have a central cup-shaped thimble 37 to have a bottom annular plate 38 from which extend upwardly six legs 39, equally spaced around the peripheral portion of the plate 38. The cup 37 is pressed downwardly through the passageway 30 to have the plate 38 disposed at a distance below the underside of the carrier 23, Fig. 5. This entrance of the cup 37 through the passageway 30 is made possible by reason of

each individual leg 39 being formed of a width which will permit it to enter between the extending ends of the walls 69 in that passage 30.

Each leg 39 is bent over the corner 40 of the carrier 23 at the inner end of each compartment 24-29 and the leg 39 is carried across the respective compartments to pass through the notches 35 and then be carried downwardly on the outside of the carrier 23 to terminate by an inturned portion having its terminus carried around the underside of the flange 23 and up on the inside thereof, Fig. 3.

That portion of each leg 39 which traverses the compartment in each instance, being centered radially of that compartment in respect to the axis of the carrier 23, is provided with a neck 41 which is made to have that cross section to give the desired rated amperage load limit. That is the neck 41 is so proportioned that the leg 39 will melt across that portion when there is an overload beyond the rated capacity.

As will be noted particularly in Fig. 3, that portion of the leg 39 which traverses across each compartment 24 is inclined upwardly from the corner or edge 40 to the notch 35 so that it is removed from contact with the floor of the compartment in each instance. Also the leg 39 in traversing the compartment has its plane generally below the plane of the top edge of the flange 34 since the legs pass through the notches 35 to so dispose the legs 39. The assembly of the fuse spider 37 with the carrier 23 as has just been described forms a unit which is then pressed frictionally into a bore 45 on the underside of a cap 46. The external diameter of this cap 46 is such that it will fit revolvably within the cup 13. The leg portions 47 which carry across the flange 33 are presented in the path of the overturned end 16 of the conductor 15 when the cap 46 is mounted within the cup 13, Fig. 3. This mounting of the cap 46 is achieved by providing the underside of the cap 46 with a downwardly extending well 48 which extends freely with clearance into the spider 37 out of contact with the upturned legs 39. The post upper part 22 extends through the bottom of this cup 48 and upwardly beyond the top side of the cap 46 to receive a button 49 screw-threadedly thereon. Between the underside of the button 49 and the bottom of the cup 48 is placed a compression spring 50 so that the cap 46 is yieldingly maintained within the cup 13.

Preferably there is a washer or suitable bearing plate 51 placed on top of the nut 19, and against which bearing plate 51 the fuse element plate 38 may ride. The plate 51 is made out of a conducting material so that there is electrical conduction between the plate 38 through the plate 51 to the post 17 and consequently the exposed head 18.

The cap 46 is provided with some means for enabling an operator to revolve it within the cup 13, such means herein being shown as two upwardly extending lugs 52 and 58.

The overturned end 16 of limited circumferential length, preferably being approximately the same as the width of the leg 39 where it comes into contact therewith. This is indicated in Fig. 5 where the conductor 15 is fragmentarily shown, with the end 16 in contact with the leg 39.

Around the outer portion of the floor 14 there is ranged in regular order a number of upwardly extending lugs 53 there being six such lugs required where there are six of the legs 39. These lugs 53 have recesses 54, Fig. 1, appearing there-

between, one side of which recess is formed by a vertically disposed wall 55, and the other side by an inclined wall 56.

The underside of the cap 46 is provided with a number of downwardly extending posts 57, Fig. 2, herein shown as three in number. Each of these posts 57 is formed to fit between the adjacent lugs 53 within the recess 54. By reason of the fact that the vertical wall 55 is presented at the side of the recess 54, the post 57 cannot be turned in a counterclockwise direction as viewed in the various figures in the drawing. However since there is the inclined floor 56 presented on the other side, the leg 57 may travel thereup as the cap 46 is turned in a clockwise direction, this travel being against the pressure of the restraining spring 50 so that in order to permit the post 57 to come up out of the recess 54 and ride on the top of the lug 53, the cap 46 will have to lift itself from the floor 14 against the resistance of the spring 50. This means that as the cap 46 is turned, the under areas 47 of the legs 39 will likewise be lifted to be out of the path of the overturned end 16 as the area 47 is carried thereto. In other words the area 47 is not so presented as to be liable to catch on the side edge of the overturned end 16, but is lifted and placed down thereon in a compressive manner as the areas 47 may be advanced one after another to come into contact with that end portion 16.

Thus it is to be seen that in the stationary position, Fig. 3, the spring 50 serves not only to seat the fuse spider plate 38 intimately on the conductor plate 51, but it also serves to bring the leg 39 and the area 47 into compressive contact with the other conductor 16, the leg in effect being compressed between that portion 16 and the underside of the cap 46.

The retaining button 49 is located between the upwardly extending members 52 and 58 in such a manner that it may be tightened or loosened therebetween as may be required. Preferably the cap 46 is made out of a transparent material as indicated in Fig. 2, so that the legs 39 may be viewed therethrough, whereby the condition of the leg in each of the compartments 24-29 may be determined by visual inspection. On one side of the top edge of the cup 13 there is provided an indicator 59, so positioned that whenever a post 57 is within a recess 54, there will be a fuse leg 39 directed theretoward. In other words the fuse leg 39 will be in that position always when the area 47 is in contact with the conductor end 16.

It is known that when the fuse leg 39 may melt under an overload, that there is in effect a slight explosive result forming gases, and the chambers 24-29 are provided to take care of that contingency, together with the opening down through the passageway 30 which is maintained around the cup 48 entering therein, the legs 39 being separated one from the other as they leave the spider plate 38 to have the openings 60 to permit the gases to travel therethrough into the much larger chamber 61 provided on the outside of that fuse element cup 37, Fig. 3. In other words the explosive effect is exerted downwardly through the passageway 30 so that the top face 70 or rather the entire underside of the cap 46 is kept clean in order to permit inspection of the individual legs 39.

Moreover there is no danger of the metal melting under the overload in any one compartment 24-29 coming into contact with the metal in an-

other compartment which would tend to vary the overload rating should that occur. The top edges of the partitions 69 are in substantial contact with the underside of the cap 46 so that there is not much tendency of the gases to be transmitted from one compartment to the other thereover. By the time the gases have entered the passage-way 30, the pressures have been so dissipated or lowered that there is no likelihood of the explosive effect in any one compartment having any effect in an adjacent compartment from the entry way provided between the vertical edges 31 of these partitions 29.

Therefore it is to be seen that I have provided a very unique, yet highly serviceable, efficient, and low cost construction. While I have shown the invention in the one embodiment, it is obvious that structural variations may be employed without departing from the spirit of the invention, and I therefore do not desire to be limited to that precise form beyond the limitations which may be imposed by the following claims.

I claim:

1. A multiple unit fuse plug comprising a body having an open cupped end with a floor from which a counterbore extends into the body; a central conducting post carried by the body extending axially through said counterbore and said cupped end; a conductor positioned on the floor of said end at a distance from the axis of said post; a cap revolvably carried in said cupped end and having a counterbore entering its underside; a fuse carrier having an external diameter to permit entrance into said cap counterbore; said carrier having a central opening therethrough and being provided with a plurality of compartments on its upper side defined by side partition walls extending radially of the axis of the carrier; a fuse element comprising a central plate, a plurality of legs radiating from the plate and extending approximately normal thereto to define a cup extending through said central opening to present said plate downwardly of said carrier, said legs each extending from said central opening radially outwardly across one of said compartments, downwardly from the outer side of the compartment and thence around inwardly on the underside of the carrier to present a contacting area thereunder adjacent the margin thereof; said areas being located in spaced relation circumferentially of the carrier at substantially the same radial distance from said axis as is said conductor.

2. A multiple unit fuse plug comprising a body having an open cupped end with a floor from which a counterbore extends into the body; a central conducting post carried by the body extending axially through said counterbore and said cupped end; a conductor positioned on the floor of said end at a distance from the axis of said post; a cap revolvably carried in said cupped end and having a counterbore entering its underside; a fuse carrier having an external diameter to permit entrance into said cap counterbore; said carrier having a central opening therethrough and being provided with a plurality of compartments on its upper side defined by side partition walls extending radially of the axis of the carrier; a fuse element comprising a central plate, a plurality of legs radiating from the plate and extending approximately normal thereto to define a cup extending through said central opening to present said plate downwardly of said carrier, said legs each extending from said central opening radially outwardly across one of said

compartments, downwardly from the outer side of the compartment and thence around inwardly on the underside of the carrier to present a contacting area thereunder adjacent the margin thereof; said areas being located in spaced relation circumferentially of the carrier at substantially the same radial distance from said axis as is said conductor; said post having an inner abutment thereon against which said plate may contact; an outer abutment on said post; and a spring between said outer abutment and said cap simultaneously urging one of said areas in contact with said conductor, and said plate into contact with said inner abutment to provide a circuit between the post through said leg to said conductor.

3. A multiple unit fuse plug comprising a body having an open cupped end with a floor from which a counterbore extends into the body; a central conducting post carried by the body extending axially through said counterbore and said cupped end; a conductor positioned on the floor of said end at a distance from the axis of said post; a cap revolvably carried in said cupped end and having a counterbore entering its underside; a fuse carrier having an external diameter to permit entrance into said cap counterbore; said carrier having a central opening therethrough and being provided with a plurality of compartments on its upper side defined by side partition walls extending radially of the axis of the carrier; a fuse element comprising a central plate, a plurality of legs radiating from the plate and extending approximately normal thereto to define a cup extending through said central opening to present said plate downwardly of said carrier, said legs each extending from said central opening radially outwardly across one of said compartments, downwardly from the outer side of the compartment and thence around inwardly on the underside of the carrier to present a contacting area thereunder adjacent the margin thereof; said areas being located in spaced relation circumferentially of the carrier at substantially the same radial distance from said axis as is said conductor; said post having an inner abutment thereon against which said plate may contact; an outer abutment on said post; and a spring between said outer abutment and said cap simultaneously urging one of said areas in contact with said conductor, and said plate into contact with said inner abutment to provide a circuit between the post through said leg to said conductor; and means spacing said areas from said conductor during turning of said cap.

4. In a multiple fuse unit, a fuse element comprising an insulating body generally disc-like in shape having upturned and downturned annular flanges around its periphery; said body having a central hole therethrough; a plurality of partition walls extending radially from said hole to said upturned flange to define compartments therebetween; a fuse member comprising a central contacting plate, a plurality of legs radiating and turned upwardly from the plate to define a thimble extending through said body hole; each of said legs extending laterally across the body from the hole across one of said compartments, across said upturned flange, downwardly, and back under said downturned flange, and upwardly inside thereof by a terminal end to present a contact area under that flange.

5. In a multiple fuse unit, a fuse element comprising an insulating body generally disc-like in

shape having upturned and downturned annular flanges around its periphery; said body having a central hole therethrough; a plurality of partition walls extending radially from said hole to said upturned flange to define compartments therebetween; a fuse member comprising a central contacting plate, a plurality of legs radiating and turned upwardly from the plate to define a thimble extending through said body hole; each of said legs extending laterally across the body from the hole across one of said compartments, across said upturned flange, downwardly,

and back under said downturned flange, and upwardly inside thereof by a terminal end to present a contact area under that flange; said upturned flange being notched at each of said compartments to receive said legs through the notches, the notches serving to space the legs circumferentially of the flange, and to space the legs above the top face of the body.
